UNITED STATES PATENT OFFICE.

RALPH E. ASBURY AND RALPH A. KENNEDY, OF HAMILTON, OHIO.

AUTOGRAPHIC REGISTER.

Application filed May 21, 1927. Serial No. 193,287.

This invention relates to autographic registers and has for a particular object thereof the provision of a device of this character which may be very readily manipulated and is so constructed that the paper may be readily arranged therein.

A further object of the invention is to provide a novel and improved friction disk mechanism for starting the movement of the papers between the issuing rollers.

In devices of this character, it has been found that the use of a knurled roller results in a burring of the duplicate sheets which is not noted when a smooth roller is employed.

Smooth rollers, however, are found inadequate in starting operation of the sheets to issue the same. Accordingly, an important object of this invention is the provision of a knurled issuing roller so constructed that it will temporarily engage the sheets to cause a movement thereof and after a predetermined movement, will release the sheets, permitting them to move under the influence of smooth surfaced issuing rollers.

A further object of the invention is to produce a device of this character which is so mounted that in order to cause an operation thereof, a key must be pressed by the thumb of the hand operating the shaft bearing the issuing rollers, this key being so located that it cannot conveniently be engaged through more than a certain portion of the rotation of the shaft, so that this roller is released and allowed to come to rest in a manner herein-after more particularly described, after it has performed its starting operation.

A still further object of the invention is to provide a novel and improved control shaft regulating mechanism, which additionally serves as a means for locking the double covers with which such machines are usually provided in their closed position.

A further object of the invention is to produce a cover construction for registers of this character of which the covers may be mounted upon a single shaft and are readily movable from open to closed position.

These and other objects we attain by the construction shown in the accompanying drawings, wherein for the purpose of illustration is shown a preferred embodiment of our invention and wherein:—

Figure 1 is a plan view of an autographic register constructed in accordance with our

invention, the upper cover being shown in 55 the open position and parts being broken away;

Figure 2 is a section on the line 2—2 of Figure 1;

Figure 3 is a section on the line 3—3 of 60 Figure 2;

Figure 4 is a detail sectional view through the pivot shaft showing the covers in their open position;

Figure 5 is a section on the line 5—5 of 65 Figure 3;

Figure 6 is a section on the line 6—6 of Figure 3;

Figure 7 is a plan view of a friction brake 70 for the disk.

Referring now more particularly to the drawings, the numeral 10 generally designates a casing, the side walls 11 of which are provided upon their interior faces with longitudinally extending racks 12 having slots 75 removably receiving the ends of paper roll shafts 13. Extending transversely of one end of the wall 14 of the casing and mounted in ears 15 carried by this rear wall is a shaft 16, one end of which is extended beyond one 80 side of the casing, as more clearly shown in Figure 1. Mounted upon this shaft are a pair of covers 17 and 18, of which the cover 17 or inner cover is of substantially the same width as the casing and the cover 18 or outer cover is wider than the casing and engages the ends of the shafts 16. Between the covers 17 and 18, at the extended end of the shaft 16, a spacer 19 surrounds the shaft 16 and maintains the cover 18 in its proper position, 85 that is to say, extended at one side of the casing 10, so that it will overlie the usual carbon spool receptacle 20 mounted on said side of the casing, for the reception of carbon sheets which are to be extended between the sheets 90 from the paper roll 13.

The inner cover 17 has adjacent its hinged edge an opening 21 for the passage of the paper sheets and extending transversely of this opening are rollers 22 corresponding in number to the paper roll 13. Extending transversely of the opening 21 is a shaft 23 having the ends thereof reduced to form pintles, one of which, indicated at 24, is relatively long. This long pintle has surrounding the same a spring 25, which extends between the bearing of the pintle and the body of the shaft and constantly urges the shaft 100 105

transversely of the opening 21, so that it frictionally bears against the bearing of the pintle.

Secured to this shaft is a leaf spring 26 extending forwardly over the rollers 22 and when the cover 18 is in closed position, it bears against this leaf spring, forcing the same downwardly upon the sheets, passing over the rollers 22 to provide a frictional drag thereon. The shaft 23 is held in any desired adjusted position because of the frictional mounting thereof and accordingly may be so positioned that it does not in any way interfere with the passage of the paper sheets over the rollers 22 in threading the machine.

Extended transversely of the casing 10 and mounted in bearings 27 carried by the side walls is a tubular shaft 28 having affixed thereto a gear 29 and a pair of feed rollers 30 having smooth peripheries. Rotatably mounted upon the shaft at its center and between the feed rollers 30 is a disk 31, one side face of which abuts a collar 32 fixed to the shaft and the opposite side face of which is formed with one member 33 of a jaw clutch. This disk, as more clearly shown in Figures 1 and 6, has a knurled periphery 34 relieved at intervals by notches 35. The cover 17 is provided with slots 36 for the passage of the peripheries of the gear 29, rollers 30 and disk 31. The knurled portions of the periphery of this disk will extend through the cover when in closed position, but when a notch 35 aligns therewith, there will be no portion of the disk projecting above the cover to engage the paper sheets passing thereover. This will be obvious by a comparison of the positions of the disk illustrated in Figures 2 and 6.

One end of the shaft 28 has secured thereto a hollow arm 37 within which is slidably a bolt 38, movement of which is limited by a pin 39. At the outer end of this arm, an operating handle 40 is mounted and in one position of the bolt, its end is extended beyond the outer end of the arm, so that it is accessible to a finger of the hand of an operator which is engaged with the handle 40. Slidable in the bore 41 of the shaft 28 is a plunger 42 having a rounded outer end 43, which engages against a cam face 44 formed upon the inner end of the bolt. Engaged with the inner ends of this plunger is one end of a spring 45 housed in the bore 41 and having its opposite ends seated against a threaded plug 46 seated in the opposite end of the shaft from the arm 37. It will be obvious that this spring by urging the plunger 42 longitudinally will serve to maintain the bolt with its outer end normally extended beyond the outer end of the arm 37. The shaft 27 between the clutch element 33 and the adjacent roller 30 has slidably mounted thereon a second element 47 of the jaw clutch and this element is connected with the plunger 42 by a pin 48 extending through a slot 49 formed in the

wall of the shaft 28. The cover 18 is provided with the usual spring-pressed roller 50 for engaging the upper surfaces of the paper sheets fast over the cover 17 to urge them into engagement with the peripheries of the rollers 30 and this roller has secured thereto a gear 51, which, in the closed position of the cover 18, meshes with the gear 29.

Extended through the side walls and paralleling the shaft 28 and the adjacent end wall 52 of the casing is a rock shaft 53, motion of which in one direction is limited by engagement of an arm 54 carried thereby with the adjacent end wall 52. This rock shaft is constantly urged in this direction by a spring 55 connected to an arm 56 carried by the rock shaft at one end and at its opposite end to the casing wall, as indicated at 57. The outer ends of this rock shaft have secured thereto latches 58 for engagement with pins 59 carried by the upper cover 18 to secure this cover in its closed position.

A friction brake is provided for the disk 35, which also comprises a means for maintaining this disk in engagement with the collar 32. This brake comprises spring arms 60 engaging at diametrically opposed points in a groove 61 formed in the hub of the disk 35 and substantially fitting this groove. The ends of these arms at one side are connected, as at 62, and at the opposite side are provided with spring loops 63 embracing the rock shaft 53. It will be obvious that in the placement of these coils about the shaft, a tension is placed against the arms 60, tending to move them in opposite directions, so that they will bind upon the sides of the grooves and tend to retard rotation of the disk. A collar 64 upon the shaft 53 limits movement of the coils 63 thereon in a direction which would permit the disk to separate from the collar 32. It will be obvious that this disk will be stationary, unless the clutch elements 33 and 47 are engaged or the paper sheets are moving while the knurled periphery of the disk projects through its opening 36. Under the latter circumstances, movement of the disk will only continue until a notch 35 registers with the opening.

Loosely mounted upon the shaft 53 adjacent the gear 29 is a sleeve 65. This sleeve has secured thereto a dog arm 66 adapted to enter between the teeth of the gear 29 and a stop arm 67 adapted to engage the casing when the dog 66 is engaged between the teeth and limit rotation of the sleeve. The sleeve 65 has also mounted thereon a control arm 68, the outer end of which is reverted to form a hook 69. The hub of the gear 29 is formed with a groove 70, with which is engaged a spring hook 71, which has frictional engagement with the base of this hook because of its resiliency and which has an arm 72, the lower end of which has a hook 73 engaging in the hook 69. The arm 68, hook 69 and dog arms 130

66 have sufficient weight to overbalance the arm 67 and to cause the sleeve 65 to rotate in a direction releasing the dog 66 from the teeth of the gear 29. If, however, the gear 29 is rotated in the reverse of the direction in which it should rotate to properly feed the sheets, the friction hook 71 will rotate therewith and the hook of the arm 72 thereof will engage against the arm 68 and move the same 10 in a direction such that the dog 66 is engaged in the teeth of the gear and rotation is checked.

It will be obvious that by employing a construction of this character, positive control of the feed mechanism is provided and a device is produced which is substantially fool-proof. Marring of the sheets is prevented by reason of the fact that traction during a major portion of the operation is provided by the smooth rollers 30, for it will be obvious that it is practically impossible for the operator to keep a finger against the end of the bolt 38 for a complete rotation of the operating handle. This being the case, as soon as the finger is released, the clutch elements will be disengaged and the disk 31 freed. If the knurled periphery is in engagement with the paper at the time of freeing of the clutch elements, rotation will continue until a notch 35 is aligned with the opening, when the paper will be disengaged and the disk 31 stationary. The ears supporting the shaft 16 have engagement with the covers 17 and 18, more clearly shown in Figure 4, whereby the cover 18 is permitted to rotate further about the pivot shaft than the cover 17, so that the cover 17 is always separated from the cover 18 when they are in open position and the introduction of the papers about the rollers 22 is thus 40 facilitated.

Since the construction hereinbefore set forth is capable of a certain range of change and modification without materially departing from the spirit of the invention, we do not 45 limit ourselves to such specific structure except as hereinafter claimed.

We claim:—

1. In a trip mechanism for autographic registers, a shaft, a pair of feed rollers secured thereto and having smooth peripheries, a starting roller rotatably mounted on the shaft having an interrupted knurled periphery, means frictionally holding the starting roller against rotation, a spring withdrawn ele-

ment for clutching the starting roller to the shaft, an arm secured to said shaft, a handle carried by the outer ends of the arm whereby the shaft may be rotated, and means for operating said clutch including a member shiftable longitudinally of the arm and normally projecting at the outer end thereof whereby it is accessible to a finger of a hand to engage with said handle.

2. In a trip mechanism for autographic registers, a hollow shaft, a pair of feed rollers secured thereto, a starting roller rotatably mounted on the shaft having an interrupted knurled periphery, means frictionally holding the starting roller against rotation, a rod extending longitudinally of the interior of the shaft to one end thereof, a clutch element for clutching the starting roller to the shaft secured to said rod, a spring within the shaft normally shifting the rod to a position where the clutch element is disengaged from the starting roller, an arm secured to said shaft, a handle at the outer end of the arm whereby the shaft may be rotated, and means for shifting said clutch rod comprising a member longitudinally shiftable upon said arm and normally projecting at the outer end thereof whereby said member is accessible to a finger of the hand engaged with the handle.

3. In a trip mechanism for autographic registers, a hollow shaft, a pair of feed rollers secured thereto, a starting roller rotatably mounted on the shaft having an interrupted knurled periphery, means frictionally holding the starting roller against rotation, a rod extending longitudinally of the interior of the shaft to one end thereof, a clutch element for clutching the starting roller to the shaft secured to said rod, a spring within the shaft normally shifting the rod to a position where the clutch element is disengaged from the starting roller, a handle carried by said end of the shaft and including a hollow arm having a hand grip at its outer end and operating members within the hollow arm and shiftable longitudinally thereof and having a cam face against which the outer end of the rod engages, the member having a portion projecting from the arm accessible to a finger of a hand engaged with the hand grip.

In testimony whereof we hereunto affix our signatures.

RALPH E. ASBURY.

RALPH A. KENNEDY.
